UNITED STATES PATENT OFFICE.

HERMAN INMON, OF HURLEY, MISSOURI.

FOLDING SCYTHE.

Application filed February 8, 1922. Serial No. 534,915.

To all whom it may concern:

Be it known that HERMAN INMON, a citizen of the United States of America, residing at Hurley, in the county of Stone and State of Missouri, has invented new and useful Improvements in Folding Scythes, of which the following is a specification.

The object of the invention is to provide a convertible mowing scythe and brush hook having means whereby the angle of the scythe blade with reference to the snathe may be varied not only to adapt the implement to be used either as a mowing scythe or a brush hook but to be arranged in edge protecting connection with the snathe and in position to facilitate sharpening on a grinding stone or like instrument without detaching the blade from the snathe; and with these objects in view the invention consists in a construction and combination of parts of which a preferred embodiment is shown in the accompanying drawings, wherein:—

Figure 1 is a view of a scythe showing the blade in full lines in its mowing and in dotted lines in its brush hook positions.

Figure 2 is a similar view showing the blade in full lines in its folded and in dotted lines in its exposed or sharpening position.

Figure 3 is an enlarged detail view partly in section of the joint or mounting of the blade.

Figure 4 is a detail view of the locking arm detached.

Figure 5 is a detail view of the pivotal end of the scythe blade.

Figure 6 is a detail view showing the manner in which a locking device engages the shoulder in the pivotal head.

Figure 7 is a detail sectional view showing the resilient means by which the locking device is maintained in position for engagement with the pivotal head.

The scythe and snathe 10 may be of any preferred or conventional form with the blade 11 pivotally mounted in a crotch or bifurcation preferably being fitted with a U-shaped rail plate 13 through which the scythe pivot bolt 14 extends, said bolt being fitted with a suitable rail or bearing sleeve

15. The scythe handle has one end bifurcated, as at 10^a. The adjacent faces of the jaws caused to be formed by the bifurcation are recessed for the reception of the U-shaped rail plate 13, as shown clearly in Figures 3 and 6.

The disk-like pivotal end or head 16 of the blade, having an opening 17' for the pivotal bolt 14 is provided with a plurality of shoulders 17, 18 and 19 with adjacent angularly disposed bearing faces 17^a, 18^a and 19^a for respective and selective engagement by the adjacent free end or tongue 20 of a locking bar 21 which is provided with an intermediate enlargement 22 having a slot 23 for the reception of a bolt 24 extending transversely through the body portion of the snathe near the fork or bifurcation thereof, the opposite or inner end of said locking bar being slotted as indicated at 25 for the reception of retaining bolts 26 upon which is fitted the washer plate 27 and which are engaged by the nuts 28. The locking bar is firmly attached by means of the bolts 26 to the snathe but is of resilient or yielding construction adapting it to be sprung outwardly from the snathe at the tongue or free end 20 to permit of its adjustment in engagement with different shoulders 17, 18 and 19 of the blade head, 80 the surface of the tongue 28 bearing upon the surfaces 17^a, 18^a and 19^a respectively according to the adjustment of the blade. One of the jaws caused to be formed by the bifurcation 10^a and one side of the U-shaped rail plate 13 have registering slots 10^b and 13^a to permit of the reception of the tongue or free end 20 of the locking bar 21, whereby the tongue may engage any one of the shoulders 17, 18 and 19. 90

Fitted upon the bolt 24 in contact with the snathe is a washer 29 upon which bears a coil spring 30 held at the desired tension by a nut 31 threaded upon the bolt 24, and enclosing said spring and adjusting nut and 95 removably threaded upon the washer 29, to protect said spring and nut and prevent the same from catching trash, grain, grass and other materials in connection with which the scythe is being used, is a guard 32 which, 100 however, is in the form of a thimble and does not interfere with the outward spring of the tongue end of the locking bar in opposition to its resilience and the pressure of the spring 30 to effect an adjustment 105 angularly of the scythe blade.

When the scythe blade is in position for engagement of its shoulder 17 by the locking bar 21 it is adapted for use as a mowing scythe whereas an adjustment of said blade 110 to effect engagement of the tongue 20 with the shoulder 18 disposes the blade at a more

acute angle with the snathe so as to adapt it for use as a brush hook as indicated by the dotted lines in Figure 1. Ordinarily it is necessary to provide two different implements for use respectively in the mowing operation and in clearing away brush or cutting close to fences or border lines whereas by the construction herein disclosed it is possible to adjust the blade from time to time to suit the different kinds of work and thus avoid the necessity of carrying a plurality of implements.

Furthermore when the scythe is not in use the blade may be folded to engage the shoulder 19 with the tongue 20 as shown in full lines in Figure 2 where the edge of the blade is locked close to the snathe and with the extremity thereof received in a suitable seat 33 therein so that said head is protected and at the same time the risk of injury to persons handling the same either alone or in connection with other implements is minimized. On the other hand when it is desired to sharpen or grind the scythe blade it may be released by the locking bar and swung to the opposite side of the snathe as indicated by the dotted lines in Figure 2 so as to expose or dispose the cutting edge downwardly to thereby avoid the necessity of dismounting the blade from the handle. In using the scythe, the blade 11 being closed when the scythe is not in use, the operator may spring the locking bar 21 laterally of the snathe in any suitable manner, for instance, by inserting an instrument (not shown) between the locking bar and the side of the snathe or handle, causing the spring 30 to be compressed. When the locking bar is in locking engagement with one of the shoulders 17, 18 and 19, the extremity of its tongue engages in the slot of the U-shaped rail plate 13. However, the tongue 20 of the locking bar engages at all times through the slot 10^b of one of the forks caused to be formed by the bifurcation 10^a. When the locking bar is sprung laterally of the snathe or handle, the extremity of the tongue moves out of the path of the shoulder with which it engages, thus permitting the blade 11 to be opened. When the blade is opened, the tongue 20 of the locking bar may be allowed to engage with either of the shoulders 17 or 18. If engaged with the shoulder 18, the blade may be held substantially at right angles to the snathe but, if engaged with the shoulder 17, the blade may be held substantially in alignment with the snathe or handle. When it is desired to close the blade, it is simply necessary to move it upon its pivot 14, it being unnecessary to use a tool or instrument to pry the locking bar laterally of the snathe. In fact, in moving the blade to a closed position, the tongue will merely yield in a direction radially from the pivot 14, the ex-

tremity of the tongue riding over the surfaces 17^a and 18^a and finally engaging with the surface 19^a and the shoulder 19.

The adjacent surfaces of the washer plate 27 and the locking bar 21 have transverse serrations or teeth 25^b and 25^a which interengage to retain the locking bar in rigid position, not only preventing a sliding movement of the bar 21 but also preventing any slight pivotal movement when the tongue rides over the surfaces 17^a and 18^a. The slots 25 in the toothed end of the locking bar are provided for the purpose of permitting the locking bar to be set, so that its tongue may engage in one of the shoulders 17, 18 and 19. The slot 23 is also elongated to not only permit longitudinal adjustment of the locking bar 21 to permit it to be set in order to properly engage any one of the shoulders, but is large enough to permit a slight movement of the locking bar when the tongue 20 springs over the surfaces 17^a and 18^a. It is obvious that if the locking bar 21 is adjusted in a direction toward the rear end of the handle or snathe, the tongue 20, when engaged with the shoulder 18, will hold the blade at a different angle than at right angles to the handle of the snathe.

Having described the invention, what is claimed as new and useful is:—

1. A scythe having a snathe, a blade pivotally mounted upon the snathe for swinging movement in the plane of its width and provided at its pivotal end with a disk head having a plurality of shoulders and adjacent bearing faces, a yielding locking bar carried by the snathe for selective engagement with said shoulders to lock the blade in different adjusted positions with relation to the snathe, and a yieldingly held longitudinally movable guide bolt extending through the snathe and through said locking bar adjacent its free end to permit yielding lateral movement of said locking bar for disengagement from said shoulders.

2. A scythe having a snathe, a blade pivotally mounted upon the snathe for swinging movement in the plane of its width and provided at its pivotal end with a disk head having a plurality of shoulders and adjacent bearing faces, a yielding locking bar carried by the snathe for selective engagement with said shoulders to lock the blade in different adjusted positions with relation to the snathe, a guide bolt extending through the snathe and said locking bar adjacent to its free end, a coil spring fitted upon said bolt for yieldingly holding the blade engaging end of the locking bar in its normal position and a nut threaded upon said bolt for tensioning the spring.

3. A scythe having a snathe, a blade pivotally mounted upon the snathe for swinging movement in the plane of its width

and provided at its pivotal end with a disk head having a plurality of shoulders and adjacent bearing faces, a yielding locking bar carried by the snathe for selective engagement with said shoulders to lock the blade in different adjusted positions with relation to the snathe, a guide bolt extending through the snathe and said locking bar adjacent to its free end, a coil spring fitted upon said bolt for yieldingly holding the blade engaging end of the locking bar in its normal position, a nut threaded upon said bolt for tensioning the spring, and a guard disposed in enclosing relation with said spring and adjacent portion of said bolt.

5 and provided at its pivotal end with a disk head having a plurality of shoulders and adjacent bearing faces, a yielding locking bar carried by the snathe for selective engagement with said shoulders to lock the blade in different adjusted positions with relation to the snathe, a guide bolt extending through the snathe and locking bar, a washer threaded upon the guide bolt in contact with the snathe, a coil spring carried by the guide bolt in bearing contact with 20 said washer, a nut threaded upon the guide bolt and tensioning the spring, and a guard enclosing said spring and tensioning nut and having threaded engagement with said washer.
